Primary Examiner — Kelley Donnelly(74) Attorney, Agent, or Firm — Sutherland Asbill & Brennan LLP(57) CLAIM

The ornamental design for a merchandiser, as shown and described.

DESCRIPTION

FIG. 1 is a perspective view of a merchandiser showing our new design;

FIG. 2 is a left side view thereof;

FIG. 3 is a front view thereof;

FIG. 4 is a right side view thereof;

FIG. 5 is a rear view thereof; and,

FIG. 6 is a top view thereof.

The broken line showings in FIGS. 1–5 are for the purpose of illustrating the environment of the design and form no part of the claimed design.
